UNITED STATES PATENT OFFICE.

JOHN B. BERARDI, OF BRIDGEPORT, CONNECTICUT.

DESIGN FOR AN AUTOMOBILE TIRE TREAD.

Application filed May 29, 1922. Serial No. 2,464. Term of patent 7 years.

To all whom it may concern:

Be it known that I, JOHN B. BERARDI, a citizen of the United States, residing at the city of Bridgeport, in the county of Fairfield and State of Connecticut, have invented a new, original, and ornamental Design for Automobile Tire Treads, of which the following is a specification, reference being had to the accompanying drawing, forming part thereof, in which—

Figure 1 is a broken face elevation of an automobile tire showing my new design, and Figure 2 a section at line 2—3 of Figure 1.

I claim:

The ornamental design for an automobile tire tread, as shown.

JOHN B. BERARDI.
